UNITED STATES PATENT OFFICE.

ARTHUR HERSCHEMANN, OF NEW YORK, N. Y.

DRAFT DEVICE FOR STEAM-BOILER FURNACES.

SPECIFICATION forming part of Letters Patent No. 740,361, dated September 29, 1903.

Original application filed October 3, 1902, Serial No. 125,735. Divided and this application filed March 4, 1903. Serial No. 146,129. (No model.)

To all whom it may concern:

Be it known that I, ARTHUR HERSCHEMANN, a subject of the Emperor of Austria-Hungary, residing in the borough of Manhattan, city, ⁵ county, and State of New York, have invented certain new and useful Improvements in Draft Devices for Steam-Boiler Furnaces, of which the following is a specification, reference being had to the drawings accompanying and ¹⁰ forming a part of the same.

My invention relates to devices for increasing the natural draft of furnaces, and more particularly is intended for use in connection with self-propelled vehicles in which steam ¹⁵ is used as the motive power; but it is obvious, of course, that it is not limited to such use and may be employed with advantage wherever a high draft in a boiler-furnace is desirable.

²⁰ It consists of the novel features and combinations hereinafter described, and more particularly pointed out in the claim.

Referring now to the drawings, Figure 1 is a vertical section of a boiler and furnace with ²⁵ which my invention is employed. Fig. 2 is a top plan view of the same.

1 designates the boiler-shell, having crown-sheet 2. Extending up within the lower end of the boiler is a fire-box or furnace 3, having ³⁰ a top 4, between which and the crown-sheet 2 are the usual tubes 5 and a larger central flue 6. By this arrangement of the fire-box a narrow space 7 is formed around the same, thus increasing the heating-surface of the ³⁵ boiler and making the generation of steam more rapid. On top of the boiler is a dome 8, into which open the flues 5 and 6, having a downwardly-extending stack 9 for the escape of the products of combustion. The ⁴⁰ steam-outlet of the boiler is the connection 10, having a suitable valve, to which is connected a superheated pipe 11, extending into the dome or superheating-chamber 8 and thence out again to the engine. In the superheating-chamber the pipe 11 may be coiled, ⁴⁵ as shown, or otherwise arranged to expose as large a surface as possible to the heat, so that the steam is superheated before it is utilized.

In order to increase the draft in the furnace or fire-box 3, the exhaust from the en-

gine is discharged therein through the exhaust-pipe 12, to which is connected the ring 13 in the fire-box, preferably conforming to the shape thereof, having openings, as 14, through which the exhaust-steam escapes. ⁵⁵ To accentuate the drafts still further, I provide a blower 15, connected by pipe 16 to any convenient source of compressed air—as, for example, a small reservoir kept charged by an air-pump operated by the engine. As ⁶⁰ will be clearly seen in Fig. 1, the pipe 16, which supplies air to the forced-draft devices, extends up into the stack and then down to the blower, so that the air is thoroughly heated before it is discharged in the ⁶⁵ ash-pit 17 under the grate 18. A valve 19, operated by a system of levers 20, controls the supply of air to the fire from the blower.

In Fig. 2, 21 designates any suitable inlet for feed-water. ⁷⁰

From the foregoing description it will be clear that the boiler by reason of its great heating-surface and the economical forced-draft devices will generate steam rapidly and yield a very high power in proportion to its ⁷⁵ size. It is therefore well adapted for automobile propulsion, as before stated. Of course the embodiment shown and described is only one of many forms which my invention may take, and I am not limited to that ⁸⁰ precise form. In this application I make no claim to the boiler itself and the steam-superheating devices, but have claimed these in an application filed by me October 3, 1902, Serial No. 125,735, of which the present application is a division. ⁸⁵

What I claim is—

The combination with a boiler and a furnace to heat the same, of a dome located on the boiler into which the products of combustion are directly discharged, a downwardly-extending smoke-stack connected with said dome, a blower operatively connected with the furnace, and a pipe for supplying air to the blower extending within the ⁹⁰ stack, as and for the purposes set forth. ⁹⁵

ARTHUR HERSCHEMANN.
